UNITED STATES PATENT OFFICE.

JOHANNA MURDO, OF MINNEAPOLIS, MINNESOTA.

FURNACE GRATE.

1,413,286.

Specification of Letters Patent. Patented Apr. 18, 1922.

Application filed February 16, 1920. Serial No. 359,047.

To all whom it may concern:

Be it known that I, JOHANNA MURDO, a citizen of the United States, resident of Minneapolis, county of Hennepin, State of Minnesota, have invented certain new and useful Improvements in Furnace Grates, of which the following is a specification.

My invention relates to a grate and may be utilized in a furnace, boiler or stove, as 10 desired.

The object of my invention is to provide for better combustion of the fuel by introducing currents of air up through the body of the fuel and preventing it from packing 15 down in a mass in the center of the grate, as usual in furnaces as ordinarily constructed.

A further object is to provide a grate which will not in any way interfere with shaking the fire or removing the ashes.

20 Other objects of the invention will appear from the following detailed description.

In the accompanying drawings forming part of this specification,

Figure 1 is a vertical sectional view 25 through the lower portion of the furnace and fire-pot, showing my invention applied thereto,

Figure 2 is a plan view of the cone grate removed from the furnace,

30 Figure 3 is a sectional view on the line 3—3 of Figure 2,

Figure 4 is a plan view of the rack or stand upon which the cone section of the grate is mounted.

35 Figure 5 is a side elevation of the supporting rack or stand for the cone section of the grate.

In the drawing, 2 represents the fire-pot of the furnace, 3 the combustion chamber, 4 a 40 base supporting the fire-pot, 5 the ash pit and 6 a grate that is supported and locked in the usual way above the ashpit. 7 is the usual jacket enclosing the furnace. 8 is a cone made preferably of a series of vertically 45 divided sections fitting together to form a conical grate section and provided with vertically arranged ribs 9 with recesses between them having slots 10 in the bottoms of the recesses leading to the space within and below the cone. These slots extend to a point 50 near the top of the cone for the purpose of introducing air through the walls of the cone at a point near the top of the body of fuel in the fire-pot. I prefer also to provide 55 ports 10' in the top of each section of the

cone to aid in the circulation of air through the grate.

The cone is hollow, open at the bottom, and fits within a circular opening 11 that is centrally arranged in the grate 6. The lower 60 walls of the cone are provided with an annular rib 12 forming a recess 13 that is adapted to receive a correspondingly shaped rib 14 formed on a ring 15 that is supported in the upper part of the ashpit by a series of 65 suitable legs 16. This ring and the supporting legs form a stationary rack stand or spider upon which the hollow cone is carried and supported in position to project upwardly through the body of fuel to a point 70 near the top thereof. The ashes are free to work down through the slots in the stationary cone and these slots may be kept clear of clinkers, slate and the like, by the insertion of a poker, or other suitable instrument, through the slots.

If desired at any time, the sections of the cone may be separated to allow an unusually large clinker or piece of slate or stone to be discharged into the ashpit beneath.

As heretofore stated, the cone is normally stationary, the grate rocking around it and the body of fire lying on the walls of the cone will receive the currents of air direct from the ashpit and will promote the rapid 85 and thorough combustion of the material resting on the cone.

In case one of the cone sections should become broken or burn out, it can be removed and a new section substituted therefor.

The cone may be made in various sizes to fit different styles and types of furnaces and may be also adapted for use with a coal burning stove, if desired.

I claim as my invention:

1. The combination, with a firepot and ashpit and a grate having a central opening supported above the ashpit, of a hollow cone fitting within the opening in said grate and projecting upwardly into the body of fuel, 100 said cone having a plurality of corrugations therein and slots in said corrugations extending from the lower portion of the cone to points near the top thereof, and a ring arranged adjacent the opening in said grate 105 and having legs resting upon the bottom of the ashpit, the upper portion of said ring forming a seat for the base of said cone.

2. The combination, with a firepot and 110

ashpit and a grate having a central opening supported above the ashpit, of a hollow cone fitting within the opening in the grate and projecting upwardly into the body of fuel and composed of a plurality of vertically separable sections, said cone having a plurality of vertical corrugations therein and slots in the bottoms of said corrugations extending continuously from points near the 5 lower end of said cone to points near the upper end thereof, said cone having a flanged base and a ring supported in the ashpit beneath said grate and whereon the base of said cone is seated.

10 3. The combination, with a fire-pot and ashpit and a grate having a comparatively large central opening extending outwardly to points near the wall of said firepot, of a comparatively large hollow cone having its 15 lower portion fitting within the opening in said grate and depending below the same and its upper portion projecting upwardly into the body of the fuel and composed of a plurality of vertically separable sections, said 20 25 sections having vertical corrugations therein

and longitudinal slots in the bottoms of said corrugations extending continuously from points near the lower end of said cone to points near the upper end thereof, a ring arranged in the ashpit beneath the opening in said grate and supporting said cone and means for supporting said ring.

4. The combination, with a fire-pot and ashpit and a grate ring fitting within said firepot and having a comparatively large 35 central opening therein extending outwardly to points near the wall of said fire-pot, of a hollow cone having a broad base fitting within said opening and depending there-through, said cone being composed of vertically separable sections, each having longitudinal slots therein, a ring supported beneath the opening in said grate and having a seat for the base of said cone, and means supporting said ring beneath said 40 45 grate.

In witness whereof, I have hereunto set my hand this 10th day of February, 1920.

JOHANNA MURDO.
